UNITED STATES PATENT OFFICE

2,116,117

PIANO

Walter Homm, Bronx, N. Y.

Application November 11, 1936, Serial No. 110,247

1 Claim. (Cl. 84—240)

This invention relates to new and useful improvements in the manufacturing of upright console spinet pianos, and it has for its special purpose to construct a new type of pianos, which contain features that are only obtainable at present in expensive grand pianos.

By the ingenious arrangement of the different parts the damper is herein manipulated by a special rail separated from the hammer, thus providing a shifting keyboard, which so far has not been possible in an upright piano.

A further advantage of this invention lies in the ability, through the present construction, as hereinafter disclosed, to reduce the height of the present uprights, one of the main objections made by a prospective buyer in these modern times.

Still another advantage lies in the introduction of a new regulating button, which in addition to the capstan screw now used in ordinary pianos makes the adjustment of the hammer swing an easy matter.

A still further advantageous feature lies in the fact that the height from the keyboard to the hammer striking point is reduced to approximately six and one-half inches, a feature made possible by the introduction of a repetition lever.

With the above and other objects in view, this invention consists of the novel features of construction, combination and arrangement of parts, hereinafter fully described, claimed and illustrated in the accompanying drawing forming part of this application, and in which similar characters of reference indicate corresponding parts, and in which:

The figure is a side elevational view of my improved arrangement in the construction of a piano showing one unit comprising the key and hammer members necessary in the operation of my device, the continuous rails, serving all keys, are shown in section, while in dotted lines are further shown the relative position of the major parts in motion.

Referring more particularly to the drawing, 45 10 indicates a key in natural position and the coordinate arrangement, including the front key pin 11, the balance key pin 12, and the capstan screw 13.

The whip 14 is hinged to a member 15, as seen 50 at 16, and said member 15 is in turn, by a screw 17, fastened to a butt rail 18. A bridge, or cross-member, 20 has one end secured to the whip 14, while a repetition lever 21 is hingedly mounted upon the other end of said bridge, as shown at 55 22, and actuated by the repetition lever spring

23. Beneath the whip is arranged an extended portion 19 adapted to engage the capstan screw 13. To the end of the repetition lever 21 is secured another member 24, and to the latter is in turn hingedly connected a jack 25; a jack-check-spring 26 engages the heel of said jack, keeping the latter in proper position.

The jack 25 engages the butt 27 of which the hammer shank 28 and hammer 29 are integral parts. To the whip 14 is furthermore secured a 10 damper spoon 30 constructed to engage the damper flange 31; said damper flange is hinged to a member 32, which by means of a screw is secured to a separate rail 34. A spring 35 secured to a small pin 33 mounted in member 32 15 keeps the damper 36 in the normal position, i. e., resting on the strings, indicated here by 37; when the key is struck the position of the same will be as partly indicated in dotted lines. The upward movement of the capstan screw forces 20 the end 38 of the repetition lever against the regulating button 39, arranged adjustably in the rail 40; after contacting said button the member 24 and the jack hingedly secured to the same, will 25 actuate the butt, and subsequently the hammer will hit the strings with a blow proportionate in force to the one applied to the key.

A rail 41 with a regulating button 42 mounted thereon is so arranged that the heel of the jack will engage said button when the hammer is at 30 a predetermined distance from the strings; a continuous movement will then force the jack to swing away from the butt, thereby releasing the pressure on said butt, and giving the hammer spring 43, secured to the rail 44 an opportunity 35 to bring the hammer back from the strings immediately after contact with the same.

A member 45 fastened to the top of the butt will on this backward movement engage a back-check 46 arranged on the whip and by holding 40 the hammer a short distance away from the strings, giving the jack actuated by the jack-spring an opportunity to fall back into normal position, when pressure is released from the key.

The damper will by the downward movement of 45 the other end of the whip 47 and the damper spoon secured thereto be removed from the strings, and spring 35 will then bring it back in normal position, when pressure is released.

It is obvious that changes may be made in the 50 form, construction and arrangement of the several parts, as shown and described herein, within the scope of the appended claims, without departing from the spirit of the invention, and I do not therefore wish to limit myself to the exact 55

construction and arrangement shown and described herein.

What I claim as new and desire to secure by Letters Patent of the United States is:

5 A device of the class described, comprising a key, a front key pin and a balance key pin co-operating with said key, and a capstan screw secured to the latter, a whip hingedly attached to a rail, and having a repetition lever mounted thereon, a jack pivotally arranged upon said repetition lever, and a check-spring engaging the

heel of said jack, two set-buttons adapted to contact the repetition lever and the heel of said jack, a spring actuating the repetition lever, a butt hinged to a member, the latter being secured to a rail, and a hammer shank and hammer forming 5 an integral part of said butt, a spring actuating the latter, a backcheck secured to the whip, and a cooperating member connected to said butt, substantially as and for the purpose set forth.

10

WALTER HOMM.
